UNITED STATES PATENT OFFICE.

BRUNO H. THEISEN AND GEORGE S. KELLER, OF MINNEAPOLIS, MINNESOTA.

STITCH-FORMING MECHANISM.

963,486.

Specification of Letters Patent. Patented July 5, 1910.

Application filed May 7, 1909. Serial No. 494,679.

To all whom it may concern:

Be it known that we, BRUNO H. THEISEN and GEORGE S. KELLER, both of Minneapolis, Hennepin county, Minnesota, have invented 5 certain new and useful Improvements in Stitch-Forming Mechanism, of which the following is a specification.

Our invention relates to stitch-forming mechanisms designed particularly for 10 leather stitching machines.

The object of the invention is to provide a simple, durable mechanism, by means of which the stitch will be accurately and quickly formed.

Other objects of the invention will appear 15 from the following detailed description.

The invention consists generally in various constructions and combination, all as 20 hereinafter described and particularly pointed out in the claims.

In the accompanying drawings, forming part of this specification, Figure 1 is a front view of the upper portion of a stitching machine, embodying our invention, 25 Fig. 2 is a side view partially in section of the same, Fig. 3 is a detail view of the stitch-forming jaws, showing the awl passing through the material, Fig. 4 is a similar view, illustrating the awl withdrawn from 30 the material and the needle inserted through the hole therein in the act of picking up the thread, Fig. 5 is a sectional view on the line X—X of Fig. 3, Fig. 6 is a detail view, showing the needle withdrawn from the material, pulling the thread with it. Fig. 7 35 illustrates a shuttle in the act of disengaging the thread from the needle, Fig. 8 is a detail view of the awl jaw.

In the drawing, 2 represents the standards supporting the mechanism of the machine, 3 a crank shaft and 4 a cam mounted thereon.

5 is a needle jaw loosely mounted on the shaft 6 and operated through a rod 7 carried by the crank shaft 3. The needle 8 is carried by the jaw 5. A secondary jaw 9 is mounted on the under side of the jaw 5 by means of a bolt 10, which prevents independent vertical movement of the jaw 9, but allows it to oscillate laterally with 50 respect to the jaw 5. A spring 11 normally tends to press the jaw 9 away from the jaw 5, and an adjusting screw 12, mounted in the jaw 5, fits within a socket in the jaw 9 and regulates the lateral movement thereof,

according to the length of stitch or the feed desired. The jaw 9 has an upwardly curved horn 13 wherein the awl 14 is secured.

15 is a work plate having an opening 16 therein, through which the awl operates. 60 The needle is provided with the usual notch to receive the thread and pull it up through the hole made by the awl.

The jaw 5 is adjustable on the shaft 6 to obtain the desired range of movement. 65

Between the standards, 2, is a post 17 (see Fig. 2) arranged to oscillate in vertical bearings, and provided with a downwardly curved arm 18 carrying a lever 19, which is provided with an anti-friction 70 wheel 20 in the path of the cam 4. An adjusting screw 21 is mounted on the arm 18 in position to engage the lever 19 and regulate its time of engagement with the cam. When the lever is engaged by the cam, the 75 post 17 will be rotated a predetermined distance, according to the position of the lever 19, with respect to its supporting arm.

At the upper end of the post 17, we provide an arm 22, which, during a portion of 80 its stroke, is adapted to engage the jaw 9 and press it toward the jaw 5 against the tension of the spring 11, the said jaw 9 swinging on the bolt 10, as heretofore described. During the down stroke of the 85 crank shaft, and its connecting rod, the oscillation of the jaw 5 will force the awl up through the leather or other material on the work plate, as indicated in Fig. 3. When the awl is withdrawn by the opposite movement of the jaw, the needle 8 will pass down through the hole made by the awl into the space beneath the work plate. To insure 90 engagement of the needle with the thread in the space beneath the work plate, we provide a plate 23 (see Fig. 5) pivoted at 24 on the work plate and adapted to swing in a horizontal plane thereunder and having a part to engage the loose end of the thread and push it around into the path of the 100 hook or notch in the end of the needle, so that when the needle ascends, it will pull the thread up through the hole in the leather made by the awl.

To operate the plate 23 at the proper 105 time, we provide an arm 25, pivotally attached at one end to the plate 23 and at its other end to the arm 22 (see Figs. 2 and 5). The movement of the arm 22 is controlled by the rocking of the post 17, so 110

that at the proper time, the plate 23 will be swung around to cause the engagement of the thread with the notch in the needle.

We claim as our invention:

5. 1. In a stitching machine, the combination, with an oscillating jaw and a needle mounted therein, of a secondary or awl jaw carried by said first named jaw and provided with an awl and arranged to swing 10 at right angles substantially to the plane of said first-named jaw, a work plate having an opening through which said awl and needle operate, a plate arranged to oscillate in a horizontal plane and engage the thread 15 and move it in the path of said needle, and a swinging arm arranged to engage and operate said awl jaw and connected with said plate to operate the same at predetermined intervals.
20. 2. In a stitching machine, the combination, with a suitable frame, of a needle jaw mounted therein, a needle carried thereby having a notched lower end, an awl jaw arranged to oscillate at an angle to said needle 25 jaw and having an awl, a rotating post mounted in said frame, an arm mounted thereon in position to operate said awl jaw, a work plate having an opening to receive said awl and needle, a pivoted plate connected with said arm and arranged to oscillate therewith and engage the thread and move it into the path of said needle, and means for rotating said post at predetermined intervals.
35. 3. The combination, with an oscillating needle jaw and a needle mounted therein, provided with a hooked lower end, of a work plate having a hole through which said needle operates, and a horizontally operating plate pivoted on said work plate and arranged to engage the thread and push it into the path of the needle and an oscillating arm with which said plate is pivotally connected.
45. 4. The combination, with an oscillating jaw and a needle mounted therein, of an awl jaw pivoted on said oscillating jaw and provided with an awl, said awl jaw swinging in a plane at an angle to the plane of said 50 needle jaw, a work plate having a hole therein, means for pressing the awl jaw into the path of the needle jaw, means for oscillating said jaw to first push the awl through the material and then withdraw it 55 and direct the needle through the hole made by the awl, and means operating below the work plate for directing the thread into the path of the needle.
60. 5. In a stitching machine, the combination, with an oscillating jaw, and a needle mounted therein, of a secondary or awl jaw carried by said first named jaw and provided with an awl and normally out of the path of said oscillating jaw, a work plate 65 having an opening through which said awl and needle operate, a plate operated to engage the thread and move it into the path of said needle, a swinging arm arranged to engage and press said awl jaw into the plane of said oscillating jaw and a link pivotally connecting said arm with said plate, for the purpose specified.
6. The combination, with an oscillating needle jaw and needle, of a work plate, a pivoted plate arranged to engage the thread under said work plate and push it into the path of the needle, an awl jaw and awl therefor, means for actuating said awl jaw to feed the goods and a link pivotally connecting said pivoted plate with said awl jaw actuating means.
7. The combination, with an oscillating needle jaw and needle, of a work plate, a thread engaging plate, an awl jaw and awl therefor, means for actuating said awl jaw to feed the goods, and means pivotally connecting said awl jaw actuating means and said thread engaging plate, for the purpose specified.
8. In a stitching machine, the combination, with a work plate, of a needle jaw and means for oscillating the same, an awl jaw pivoted on said needle jaw, a spring normally holding said awl jaw out of the plane of said needle jaw, means for pressing said awl jaw toward said needle jaw, a plate pivoted beneath said work plate and adapted to engage the thread, and a link pivotally connecting said plate with said awl jaw pressing means, substantially as described.
9. In a stitching machine, the combination, with a work plate, of a pivoted thread engaging plate, a needle jaw, an awl jaw having an oscillating movement with said needle jaw, and a similar movement independent of said needle jaw, means for operating said awl jaw independently of said needle jaw, and means connecting said thread-engaging plate with said awl jaw operating means.
10. In a stitching machine, the combination, with a work plate, of a thread engaging plate, a needle jaw, and needle, an awl jaw and awl carried thereby, an arm arranged to engage and actuate said awl jaw to feed the goods, and a link connecting said arm and said thread engaging plate, for the purpose specified.
11. In a stitching machine, the combination, with a work plate, of a thread engaging means, a needle jaw and needle, and awl jaw and awl, a rotating post, means carried thereby and arranged to actuate said awl jaw, and means pivotally connecting said thread engaging means and said awl jaw actuating means, for the purpose specified.
12. The combination, with a work plate of a needle jaw and needle, an awl jaw and awl therefor, a thread engaging plate disposed near said work plate, a rotating post

means carried thereby for actuating said awl jaw to feed the goods, means pivotally connecting said awl jaw actuating means and said thread engaging means, an arm mounted on said post, an actuating cam therefor, and means for regulating the stroke of said arm.

13. The combination, with a work plate, of a needle jaw and needle, an awl jaw and awl, a thread engaging plate disposed near said work plate, means for actuating said

awl jaw to feed the goods, and means connecting said awl jaw actuating means and said thread engaging plate.

In witness whereof, we have hereunto set our hands this 24th day of April, 1909.

BRUNO H. THEISEN.
GEORGE S. KELLER.
